J. Rebhun,

Clarinet.

No. 93,005.

Patented July 27, 1869.

United States Patent Office.

JACOB REBHUN, OF NEW YORK, N. Y.

Letters Patent No. 93,005, dated July 27, 1869.

IMPROVEMENT IN CLARINETS.

The Schedule referred to in these Letters Patent and making part of the same.

To all whom it may concern:

Be it known that I, JACOB REBHUN, of the city, county, and State of New York, have invented a new and improved Clarinet; and I do hereby declare that the following is a full, clear, and exact description thereof, which will enable others skilled in the art to make and use the same, reference being had to the accompanying drawings, forming part of this specification, in which—

Figure 1 represents a side view of my improved clarinet.

Figure 2 is a face view of the same.

Figure 3 is a detail longitudinal section of the same.

Figures 4 and 5 are transverse sections of the same, taken respectively on the planes of the lines $x x$ and $y y$, fig. 2.

Similar letters of reference indicate corresponding parts.

The object of this invention is to so construct and arrange the keys and levers of a clarinet, that difficult passages, which could heretofore not be produced, such as various kinds of trills and shakes, can, without difficulty, be obtained, and that the fingers will be relieved of the great strain to which they are subjected on the ordinary instruments now in use, while playing certain difficult passages.

The invention consists in the arrangement of certain new keys and levers, and in a new manner of disposing the same, with the object of giving the player a more thorough control over the instrument.

A, in the drawing, represents the tubular body of the clarinet. It is provided with the apertures and mouth-piece, in the ordinary or suitable manner, and is composed of sections or made of one single piece, as may be desired.

B is the lower B-key, attached to a jointed double-pivot lever, C, which is, at its upper end, held up by a spring, so that the key will be automatically held open, to play the note C.

D is the C-key, attached to a swivel-pin, a, which has a handle, b, and a projecting ear, c.

An ear, d, on the lever, C, fits under the ear c. When, therefore, the key B is closed by depressing the upper end of the lever C, the ear c will be swung up, and thereby the key D will also be closed, whereby the tone B is played.

E is the ordinary C-sharp key. It is secured to a single lever, F, which has an ear, e, fitting under the ear c, so that when the key E is opened, it will close the key D.

I have provided a second C-sharp key, G, which is attached to a single pivot-jointed lever, H, whose handle is near that of the key D.

I is a transverse plate, pivoted to the tube A, and provided with arms, which reach over the levers F and H. When the key E is raised, it will raise its side of the plate I, and thereby depress the key G.

Between the levers C and F is provided a long lever, J, which has its transverse handle, f, extend over those of C and F, and which, when held down, raises the plate I, to close the key G.

It has also a projecting ear, g, fitting under c, to close the key D, together with G.

When the handles of the keys D and G are held down, the C-key is closed, and the key G opened. Then, by oscillating the lever C, it will alternately close and open the keys B and G, as it acts on the plate I.

The otherwise very difficult B-C-sharp trill is thus produced.

The lever J is not to be held down with such force that it will close the key B and open E.

K is the ordinary E-flat key, arranged in suitable manner. I have provided a second E-flat key, L, opposite to it. It is attached to a jointed double-pivot lever, M.

A separate key, N, below L, is provided to supply the necessary air, and is raised simultaneously with L, as the lever M rests on N, so that the lever O of N, when held against the tube, serves to open both keys, L N.

The position of the second E-flat key is such that it can be operated conveniently in places where the original one could not be readily played.

All the hereinbefore-described keys are held closed by springs, except the keys B and D, which are held open.

In order to produce the difficult G-sharp-A trill of the higher, as well as the lower octaves, I have arranged, above the ordinary well-known G-sharp key, not shown in the drawing, a second key, P, for the higher, and Q for the lower octave.

The levers of these keys reach, with their handles, close to the handles of C F J, so that they can be conveniently played in conjunction with either of the other keys.

When one of these keys P Q is opened, together with the G-sharp key belonging to the same, the tone A will be produced, and by alternately oscillating such G-sharp key, and the key P or Q, belonging thereto, the G-sharp and A trill will be produced, which was heretofore very difficult, on account of the necessity of playing on the hole provided for A.

Having thus described my invention,

I claim as new, and desire to secure by Letters Patent—

1. The B-key B, connected with the lever C, which has the ear d, to actuate the C-key D, substantially as herein shown and described.

2. The lever F of the C-sharp key E, when provided with the ear e, to close the key D, as set forth.

3. The lever J, pivoted between the levers C and F, to act at once on the keys D and G, substantially as herein shown and described.

4. The plate I, pivoted to the clarinet, to close the key G, and to produce the B-C-sharp trill, substantially as herein shown and described.
5. The application, to a clarinet, of a second C-sharp key, G, to operate substantially as herein shown and described.
6. The application, to a clarinet, of a second E-flat key, L, substantially as herein shown and described.
7. The combination of the secondary E-flat key L

with the key N and levers M, substantially as herein shown and described.

8. The keys P and Q, or either, provided, together with the G-sharp keys, to produce A and the G-sharp and A trill, substantially as herein shown and described.

JACOB REBHUN.
